HAIR CLIPPING DEVICE

Theodore Steinbach, Millburn, N. J.

Application April 6, 1938, Serial No. 200,321

13 Claims. (Cl. 30—43)

The invention is concerned with close cutting hair clippers, popularly referred to as "dry shavers."

The main object of the invention is to produce a device of this character which would be simple in construction, have only a few parts, easily replaced, and which would, for these reasons, be available to a larger number of users because of the low cost of manufacture. It is, at the same time, an object of the present invention to accomplish the aforesaid improvements in structure and reduction in cost of manufacture without in any way detracting from the efficiency of the device. Among other objects may be mentioned a novel and simple way of securing the shear plate, i. e., the plate in which the stationary shearing teeth are located, to the cutting head of the appliance; greatly facilitated means of egress of the clipped hair from the cutting head, with the concomitant avoidance of all clogging therein; and a simplified, rugged driving mechanism. Other objects of the invention will become apparent from the specification which follows.

In the drawing, Fig. 1 is a plan view of a characteristic embodiment of the invention, after removing one half of the housing for the mechanism. Fig. 2 is a view of the same device looking at one end of the head, the lower portion of the structure being broken off. Fig. 3 is an enlarged cross section of the head taken along the line 3—3 of Fig. 1. Fig. 4 is a similarly enlarged top view of the device, partly in section with the cutter removed. Fig. 5 is a cross section of the same device taken along the line 5—5 of Fig. 4. Fig. 6 is a partial top view of the shear plate, with the slots going all the way across instead of being separated by a solid strip, as in Fig. 3. Figs. 7-11 are details showing cross sections of several modifications of the shear plate. Figs. 12-13 are details showing fractional top views of the shear plate, with flaring ends of the slots, the slots in Fig. 12 being separated by a solid strip, and going all the way across in Fig. 13. Fig. 14 is a cross section of a modified head. Fig. 15 is a diagrammatical view of a modified driving mechanism.

Referring to the figures in detail, 1 is a housing and 2 a head removably attached to the housing 1, as by means of a screw 6. The head 2 comprises a block 7 which fits into a recess 8 of the housing 1 and is secured against longitudinal displacement by a rib 4 lodged in a recess 5 of the block 7. At each end of the block 7 are standards 3, on either side of a longitudinal groove 9

in the block 7. The groove 9 is widened at the ends by the addition of flaring recesses 10 in the standards 3.

The shearing operation takes place between the teeth formed by slots 17 in a shear plate 15, and the teeth 22 of a cutter 21. The shear plate 15 has longitudinal lips 18 extended at their ends into legs 19 which rest on the block 7, in the groove 9, between the standards 3. The lower portions 20 of the legs 19 spread outwardly against the walls of the recesses 10 and, in the assembly, are forced in between the standards 3, effectively securing the legs 19 and the entire shear plate 15 in position. The slots 17 of the shear plate 15 extend into the lips 18, but terminate short of their outer edges. The slots of the shear plate may be separated by a solid strip, as in Fig. 3, or may go all the way across, as in Fig. 6.

20 The driving mechanism is an oscillator of standard type for an A. C. supply. It consists of an electromagnet 26 secured to the housing 1, as by means of screws 25, and an armature bar 26, one end of which, 27, is pivoted in a socket 28 on a bracket 29 secured to the housing 1 by screws 30, and the other end, 28, is lodged in a hole in the cutter 21. The oscillation of the armature bar 26 is effected by the intermittent attraction of the electromagnet 26 and repulsion due to the 25 action of a spring 31, the resiliency of which is such as to prevent the armature bar from making actual contact with the pole of the electromagnet, thus avoiding the noise and vibration caused by repeated impacts. Means for adjusting the 30 travel of the armature bar comprise a standard screw and slot arrangement 33 on a bracket 32 of the housing 1.

The block 7 is provided with a hole 11 for the passage of the armature bar 26, and two additional holes 12 for housing the resilient means 13 for urging the cutter 21 onto the shear plate 15.

40 The side walls 14 of the block 7 are tapered, the upper edges extending slightly beyond the lips 18 of the shear plate 15, but leaving an open space 45 between the lips 18 and the walls 14. This arrangement affords the clipped hair a ready egress from the head 2, through the open space between the walls 14 and lips 18, and down the incline of the walls 14.

45 From the terminals 34, 35, connected to a supply of alternating current, leads 36, 37, complete the electrical circuit. However, the lead 36, connected to the terminal 34, has an intermediate binding post 38, the purpose of which will be 50 presently explained.

When the current supply is from a direct current source, an interrupter is added to the mechanism. Such an interrupter is diagrammatically illustrated in Fig. 15. It is mounted on a bracket 39 which is secured to the housing 1 by means of the same screws 25 which secure the electromagnet 24 thereto. The bracket 39 has a flange 40 carrying a contact member 41. A cooperating contact member 42 is carried by a flat spring 43, one end of which is secured to the bracket 39, as by a screw 44. The other end of the spring, denoted by the numeral 45, passes through an opening 46 in the armature bar 26, under an acute angle therewith. The binding post 38 of Fig. 1 is indicated in Fig. 15 in dotted line. The lead 36 is now connected to the spring 43 at 44. In the figure, the contact members 41, 42, are shown in contact. The path of the current is from the terminal 34, over the lead 36, spring 43, and contact members 41-42, to the electromagnet 24, and from the electromagnet 24 over the lead 37 back to the terminal 35. The armature bar 26 is attracted by the electromagnet 24, whereupon, owing to the inclination of the end 45 of the spring 43, in the opening 46 of the armature bar 26, the contact member 42 will be raised out of contact with the contact member 41, thus breaking the circuit.

It will be observed that all one has to do to adapt the type of device shown in Fig. 1 to the one illustrated in Fig. 15, is to provide the armature bar 26 with the opening 46, which may be done in all cases, whether the opening is to be used, or not. The interrupter can then be added to the mechanism whenever desired, without changing the standard mechanism. To change the type of device from one adapted for use with an A. C., to one adapted for use with a D. C., all one needs to do is to screw the bracket 39, with its auxiliary parts, onto the plate carrying the electromagnet 24, using the same screws and screw holes, disconnect the lead 36 from the binding post 38, and connect it to the spring 43 at 44.

When the shear plate 15 is of the form shown in Figs. 10, 11, the teeth of the cutter 21 will, of course, be bounded by a correspondingly curved surface.

It is usual to make the open ends of the slots 17 flaring, at the same time beveling or rounding the ends of the teeth of the shear plate 15, as illustrated in Figs. 12 and 13, to facilitate the entry of hair into the cutting mechanism.

The upper portions of the standards 8 are rounded and extend sufficiently far from the ends of the shear plate 15 to protect the skin from possible injury by the corners of the shear plate.

When current is supplied to the device in the manner above indicated, the end 23 of the armature bar 26 will cause the cutter 21 to have a reciprocating motion, as is well understood in the art.

In Fig. 14 is illustrated another way of securing the shear plate 15 in the block 1. Instead of making the lower portions of the legs 19 flaring, the legs are provided with bulging portions 50, and the standards 8 are made with recesses 10' to receive the bulging portions 50 which are snapped into the recesses 10'.

It is believed that the structure of the device and its operation are so simple as to require no further explanation.

I claim:

1. In a device of the class described, a head comprising an oblong block, upstanding standards at the ends of said block, a shear plate

fitting in between said standards, legs at the ends of said shear plate having outwardly flaring portions, said standards being provided with recesses to receive said flaring leg portions, longitudinal lips on said shear plate overhanging the side walls of said block and spaced therefrom to permit egress of the clipped hair, teeth formed by transverse slots in said shear plate extending into said lips but terminating short of their outer edges, a cutter movable in said block under said shear plate having teeth in sliding contact with the teeth of said shear plate, and means for moving said cutter relatively to said shear plate.

2. In a device of the class described, a head comprising an oblong block, upstanding standards at the ends of said block, a shear plate fitting in between said standards, legs at the ends of said shear plate having bulging out portions, said standards being provided with recesses to receive said bulging leg portions by a snap action, longitudinal lips on said shear plate overhanging said block and spaced therefrom to permit egress of the clipped hair, teeth formed by transverse slots in said shear plate extending into said lips but terminating short of their outer edges, a cutter movable in said block under said shear plate having teeth in sliding contact with the teeth of said shear plate, and means for moving said cutter relatively to said shear plate.

3. In a device of the class described, a head comprising an oblong block, a resilient member including a shear plate fitted into said block, an obstruction to the passage of said resilient member into and out of said block surmountable by the resiliency of said resilient member, teeth formed by slots in said shear plate, a cutter movable in said block under said shear plate, teeth in said cutter in sliding contact with the teeth of said shear plate, and means for moving said cutter relatively to said shear plate.

4. In a device of the class described, a head comprising an oblong block having a central longitudinal groove, a resilient member including a shear plate fitted into said block, an obstruction to the passage of said resilient member into and out of said block surmountable by the resiliency of said resilient member, teeth formed by slots in said shear plate, a cutter movable in said groove and having teeth in sliding contact with the teeth of said shear plate, and means for moving said cutter relatively to said shear plate.

5. In a device of the class described, a head comprising an oblong block having a central longitudinal groove, upstanding standards at the ends of said block, a resilient member including a shear plate between said standards, an obstruction to the passage of said resilient member between said standards surmountable by the resiliency of said resilient member, teeth formed by slots in said shear plate, a cutter movable in said groove and having teeth in sliding contact with the teeth of said shear plate, and means for moving said cutter relatively to said shear plate.

6. In a device of the class described, a head comprising an oblong block having a central longitudinal groove, upstanding standards at the ends of said block, a shear plate provided with resilient legs fitting between said standards, obstructions to the movement of said legs between said standards surmountable by the resiliency of said legs, teeth formed by slots in said shear plate, a cutter movable in said groove and hav-

ing teeth in sliding contact with the teeth of said shear plate, and means for moving said cutter relatively to said shear plate.

7. In a device of the class described, a head comprising an oblong block, a resilient member including a shear plate in said block, an obstruction to the passage of said resilient member into and out of said block surmountable by the resiliency of said resilient member, longitudinal lips on said shear plate, teeth formed by transverse slots in said shear plate, said slots extending into said lips but terminating short of their outer edges, a cutter movable in said block under said shear plate, teeth in said cutter in sliding contact with the teeth of said shear plate, and means for moving said cutter relatively to said shear plate.

8. In a device of the class described, a head comprising an oblong block, upstanding standards at the ends of said block, a resilient member including a shear plate between said standards, an obstruction to the movement of said resilient member between said standards surmountable by the resiliency of said resilient member, longitudinal lips on said shear plate, transverse teeth formed by slots in said shear plate, said slots extending into said lips but terminating short of their outer edges, a cutter movable in said block under said shear plate, teeth on said cutter in sliding contact with the teeth of said shear plate, and means for moving said cutter relatively to said shear plate.

9. In a device of the class described, a head comprising an oblong block, upstanding standards at the ends of said block, a shear plate, longitudinal lips on said shear plate formed at their ends into resilient legs fitting in between said standards, obstructions to the movement of said legs between said standards surmountable by the resiliency of said legs, teeth formed by transverse slots in said shear plate, said slots extending into said lips but terminating short of their outer edges, a cutter movable in said block under said shear plate having teeth in sliding contact with the teeth of said shear plate, and means for moving said cutter relatively to said shear plate.

10. In a device of the class described, a head comprising an oblong block, a resilient member including a shear plate in said block, an obstruction to the movement of said resilient member in said block surmountable by the resiliency of said resilient member, said block having inwardly tapering outer walls, longitudinal lips on said shear plate overhanging said tapering walls, teeth formed by transverse slots in said shear plate, said slots extending into said lips but

terminating short of their outer edges, a cutter movable in said block under said shear plate having teeth in sliding contact with the teeth of said shear plate, and means for moving said cutter relatively to said shear plate.

11. In a device of the class described, a head comprising an oblong block, upstanding standards at the ends of said block, said block having inwardly tapering outer walls between said standards, a resilient member including a shear plate between said standards, an obstruction to the movement of said resilient member between said standards surmountable by the resiliency of said resilient member, longitudinal lips on said shear plate spaced from said walls, teeth formed by transverse slots in said shear plate, said slots extending into said lips but terminating short of their outer edges, a cutter movable in said block under said shear plate having teeth in sliding contact with the teeth of said shear plate, and means for moving said cutter relatively to said shear plate.

12. In a device of the class described, a head comprising an oblong block, upstanding standards at the ends of said block, a resilient member including a slotted shear plate between said standards, an obstruction to the movement of said resilient member between said standards surmountable by the resiliency of said resilient member, said standards having rounded portions extending beyond the ends of said shear plate to protect the skin from injury by the corners of said shear plate, a cutter movable in said block under said shear plate having teeth in sliding contact with the teeth of said shear plate, and means for moving said cutter relatively to said shear plate.

13. In a device of the class described, a head comprising an oblong block having a central longitudinal groove, upstanding standards at the ends of the block, a resilient member including a shear plate between said standards, an obstruction to the movement of said resilient member between said standards surmountable by the resiliency of said resilient member, longitudinal lips on said shear plate, said block having inwardly tapering outer walls between said standards extending beyond said lips and leaving an open space between said walls and said lips, teeth formed by transverse slots in said shear plate, said slots extending into said lips but terminating short of their outer edges, a cutter movable in said block under said shear plate having teeth in sliding contact with the teeth of said shear plate, and means for moving said cutter relatively to said shear plate.

THEODORE STEINBACH.
